Edna Sobley Tipton
By Edward P. Luman
Attorney

UNITED STATES PATENT OFFICE

EDNA SIBLEY TIPTON, OF NEW YORK, N. Y.

VANITY CASE

Application filed July 16, 1932. Serial No. 622,900.

The object of this invention is, to supply the demand for a compact, conveniently-arranged vanity case which shall include a comb together with compartments for make-up such as face powder, rouge, lipstick etc., also a mirror, and shall, furthermore, be suitable for carrying in the pocket or in a lady's handbag.

My improved vanity case is clearly illustrated in the accompanying drawing in which:

Fig. 1 is a face view of the side of the case which carries the comb.

Fig. 2 is a face view of the reverse side 15 of the case.

Fig. 3 is an edge view of the case.

Fig. 4 is an end view of the adjacent end of Fig. 3.

Fig. 5 is an edge view of the case with 20 the comb and the cover for the make-up compartments in a partially opened position.

Fig. 6 is a central, longitudinal section through the body of the compact, also through the cover of the make-up compartments, but the comb is not here shown in section.

Fig. 7 is an end view of the adjacent, hinge end of the case.

Fig. 8 is a section on line VIII—VIII of 30 Fig. 6.

This case may be made of any suitable material, such as metal, or any of the numerous compositions, some of the best known of which are commercialized under the trade 35 mark names of "Viscoloid", "Bakelite" etc.

The construction shown in the drawing consists of the case body 1, of substantially flat rectangular form, in one side of which a depression is formed by a frame 2 which extends around two sides and one end of said body; this depression receives or nests the comb 3, flatwise therein and conforms closely to the outline of said comb except at the hinge end, which is open to permit the comb 40 to be opened to the service position, which it is caused to assume by swinging its free end through a half circle; the hinge of the comb is shown at 4; the free end of the comb is provided with a tongue 5, which fits closely into a niche 6, provided therefore in the

adjacent portion of said frame 2, and whereby the comb is yieldably retained in the closed position.

The face of said body 1, opposite to that which carries the comb, is shown as being 55 formed to provide three compartments or receptacles 7, 8 and 9; receptacle 7 is for the purpose of containing face powder in cake form; receptacle 8 is intended to hold rouge, preferably in paste form; receptacle 9 is intended to contain lipstick in any suitable form. As a cover, 10, for said compartments, a sheet of stainless steel is employed, one or both sides of which may be polished 60 to form a mirror; this cover is provided at 65 one end with a hinge 11.

Between the hinge points 4 and 11, body 1 is extended outwardly at 12 to form a stop or backing for said comb 3 and cover 10 when they are in the open position, and whereby 70 both said members are prevented from swinging, when opened, through an extent greater than a semicircle.

Said cover 10, is provided with a securing 75 tongue 13, and in the juxtaposed portion of said body 1 is formed receiving niche 14 into which said tongue 13 fits sufficiently tight to yieldably retain the cover in its closed position.

I claim the following:

1. A vanity case consisting in combination, of a body of flat substantially rectangular, oblong shape, having in one of the larger sides thereof a depression for the reception of a comb, a comb nested flatwise in said depression and hinged at one of its ends to one end of said body, there being a plurality of receptacles formed in the reverse side of said body, and a cover for said receptacles consisting of a mirror hinged at one of its ends to said body.

2. A vanity case comprising in combination, a body of flat substantially rectangular, oblong shape having in one of the larger sides thereof a depression for the reception of a comb, a comb occupying said depression, said comb being hinged at one of its ends to one end of said body; a plurality of receptacles formed in the reverse side of said body; and a cover for said receptacles 95 100

hinged to said body adjacent the hinge point of said comb; said body being formed into a stop whereby said comb and said cover are limited in the extent of their respective opening movements.

In testimony whereof I affix my signature.

EDNA SIBLEY TIPTON.
